UNITED STATES PATENT OFFICE.

ENOCH OHNSTRAND, OF MOHAWK, NEW YORK, ASSIGNOR TO LIBRARY BUREAU, OF CAMBRIDGE, MASSACHUSETTS, A CORPORATION OF NEW JERSEY.

CABINET CLOSURE.

Application filed April 12, 1922. Serial No. 551,958.

To all whom it may concern:

Be it known that I, ENOCH OHNSTRAND, a citizen of the United States of America, and resident of Mohawk, in the county of 5 Herkimer and State of New York, have invented new and useful Improvements in Cabinet Closures, of which the following is a specification.

This invention relates to cabinet closures 10 and more particularly to cabinets, such as filing cabinets, of the type having a sliding tray or drawer movable into and out of housed position within the cabinet.

When such a cabinet is moved it occasionally 15 happens that a drawer accidentally comes open, and for use on shipboard means must be provided to prevent the drawers from sliding open when the vessel pitches or rolls.

20 Objects of the invention are to prevent the accidental opening of cabinets of the class described, to conceal the actuator for the latching mechanism in order that the appearance of the cabinets may not be marred 25 thereby, to arrange the actuator so that it is operated in grasping the cabinet handle in the usual way, to provide a latching mechanism which is simple in construction and may be readily installed, and in general to 30 improve devices of the class described.

For the purpose of illustrating the invention one concrete embodiment thereof is shown in the accompanying drawing, in which:—

35 Figure 1 is a plan view;

Figure 2 is a rear elevational view of the drawer head; and

40 Figure 3 is a vertical section substantially on the line 3—3 of Fig. 2 but showing portions of the cabinet of which the drawer forms a closure in dotted outline.

The embodiment of the invention shown 45 for the purpose of illustration comprises a cabinet closure in the form of a filing drawer having a head A, sides B, back C, bottom D, follower E, rod F for holding guides in the drawer, and an index holder G. As shown, the drawer is of conventional appearance.

The mechanism by which the cabinet closure 50 is retained within the cabinet, the sills of which are shown in dotted outline in Fig. 3, is mounted upon the inner side of the face plate 4 of the drawer head A and is shown in elevation in Fig. 2 and in section in Fig. 55 3. This mechanism is mounted upon a plate

5 having struck up marginal portions forming flanges 6 and adapted to be fastened to the front of face plate 4 by means of nuts 7 upon the bolt ends 8 of the drawer handle 9 which, as shown in Figs. 1 and 2 is loop-shaped or U-shaped. Plate 5, as shown in Fig. 3, occupies but a portion of the space between the front face 4 and the rear plate 10 of the drawer head. This rear plate, has flanged portions 11 forced beneath or behind 60 the flanges 12 and 13 upon face plate 4, flanges 12 being formed by bending over the marginal portions of face plate 4 into parallel relation therewith. The flanges 13 at the bottom of face plate 4 are inclined in 65 wardly as shown in Fig. 3.

The latching mechanism comprises a bolt 14 mounted for sliding movement upon the plate 5 by the provision of a struck up loop 15 thereon, and a slot 16 in lower flange 6. 70 Pivoted to bolt 14 by means of a pin 17 is a bell crank lever 18 pivoted at 19 to plate 5 and having an integral actuator portion 20 extending through slots 21 in plates 4 and 5 so positioned that the actuator is within 75 the loop or curve of the handle 9 at the left side thereof as shown in Fig. 1. Lever 18 may have a washer 22 thereon adjacent the point where it is bent to form the actuator 20. Pivot 19 which is fast in plate 5 has a 80 spacer 23 to compensate for the thickness of washer 22. In order normally to hold the bolt 14 in operative position to engage a suitable recess in sill G of the cabinet, a coil spring 24 is provided attached at one end to 85 the lower arm of bell crank lever 18 and at the other end fast to a projection 26 on plate 5. This projection may take the form of a struck up portion of the plate as shown in 90 Figs. 2 and 3.

95 In assembling the device, the bolt 14 is first slipped under loop 15 until the hole in which pivot 17 is made fast is above a hole a in plate 5 through which a suitable tool may pass to securely rivet loop 15 in place 100 in bolt 14. Plate 5 is then placed in juxtaposition to face plate 4 with slots 21 in registry. Bell crank lever 18 is then inserted through the slots 21 from the outer side of plate 4 and washer 22 is slipped thereover. 105 If difficulty is experienced in setting bell crank 18, the bend therein adjacent the actuator or trigger 20 may be made after the crank is inserted through the slots. The bell crank is then made fast upon pivot 19 110

and connected to bolt 14 by pin 17; spring 24 is applied. Handle 9 is fast to the outer face of the plate 4 at any time after lever 18 is inserted, the securing nuts 7 for the 5 handle clamping the plate 5 which supports the latching mechanism securely on face plate 4. Back 10 is then made fast to the drawer head and the rest of the drawer is made fast to the head. The lower edge of 10 plate 10 cooperates with loop 15 and slot 16 in flange 6 to guide bolt 14 in its reciprocation.

From the above it will be clear that the 15 latching device consists of two parts, may be cheaply constructed and assembled and is very effective for the purpose desired. The actuator 20 being positioned within loop handle 9 is almost entirely concealed and does not detract from the appearance of the drawer head. Moreover its 20 position is such that it is readily operated when the handle is grasped, the particular form of actuator shown being adapted to be operated by pressing upon or squeezing 25 the handle with the thumb and forefinger.

I claim:—

1. A cabinet closure having a face plate, a back plate, a loop handle on said face plate, latching mechanism mounted between said plates comprising a bolt, a bell crank having one arm pivotally attached to said bolt and the other arm having a portion extending through a slot in said face plate to the exterior thereof within 35 said loop handle to form an actuator for operating said bolt when said handle is grasped.

2. A cabinet closure having a loop handle on the front thereof, a plate on the back 40 of said closure, fastening means for the handle arranged securely to support said plate, a latch mechanism assembled upon said plate, and an actuator integral with one of the elements of said latch mechanism extending through slots in said plate and closure and disposed within said loop handle.

3. A drawer for cabinets and the like having a head, a loop handle on one side of said head, a latch mechanism assembled 50 on a plate and fast as a unit upon the other side of said head, one element of said latch mechanism having a part extending through a slot in said head to a position within said handle to serve as an actuator for said 55 mechanism.

4. A drawer for cabinets and the like having a head provided with a back spaced from said head, a latch mechanism mounted upon a plate for insertion as a unit in the 60 space between said back and said head, a loop handle on said head, and a latch actuator within said loop handle and operatively connected to said latch mechanism.

5. A drawer for cabinets or the like having a head comprising a face plate and a back plate in spaced relation, a loop handle upon the exterior of said face plate, fastening means for said handle serving to securely hold a third plate in the space between said face and back plates, latching mechanism on said third plate comprising a reciprocable bolt and a member for actuating the latter, said member having a portion extending to the exterior of said face 75 plate adjacent said handle in position to be actuated when said handle is grasped.

6. A drawer for cabinets and the like having a face plate, a loop handle on the exterior thereof, fastening means for said 80 handle serving to securely hold a flanged plate upon the inner side of said face plate, guide means on said flanged plate including a loop thereon and a slot in one of the flanges thereof, a bolt reciprocable in said 85 guides, a bell crank lever for actuating said bolt, means normally retaining said bolt in extended position, and an actuator within the loop of said handle operatively connected to said bell crank for retracting said 90 bolt when said handle is grasped.

Signed by me at Ilion, N. Y. this 10th day of April, 1922.

ENOCH OHNSTRAND.
